S. A. HAMNETT

SEAL AND MEANS FOR MAKING THE SAME

Filed April 20, 1925

UNITED STATES PATENT OFFICE.

SAMUEL A. HAMNETT, OF LOS ANGELES, CALIFORNIA.

SEAL AND MEANS FOR MAKING THE SAME.

Application filed April 20, 1925. Serial No. 24,456.

This invention relates to seals.

The general object of the invention is to provide an improved seal together with an improved method and means for manufacturing this seal.

One of the specific objects of the invention is to provide a novel seal comprising a fixed die and a movable die.

Another object of the invention is to provide an improved step in the method of manufacturing seals.

Another object of the invention is to provide an improved heating device for heating parts of a seal to render one of the dies plastic.

An additional object of the invention is to provide an improved die heating implement wherein a novel means is employed for controlling the temperature of the implement.

Another object of the invention is to provide an improved contractile band for holding the parts of a seal in proper position while one of the dies is being formed.

The above objects together with other objects of the invention will be apparent from the following description taken in connection with the accompanying drawings wherein Fig. 1 is a side elevation of a seal embodying the features of my invention;

Fig. 2 is a top plan view partly in section showing the relation of the various parts; Fig. 3 is an enlarged detail partly in section showing the heating member in place; Fig. 4 is a perspective view of the contractile band; Fig. 5 is a top plan view partly in section showing a modified heating unit; Fig. 6 is a side elevation partly in section showing the modification and Fig. 7 is a perspective view of the bakelite disc.

Referring to the drawings by reference characters, I have shown the body of a seal with which my invention is adapted to be used at 10. This seal includes a base 11 and an operating handle 12. The handle 12 operates an upper die 14 of brass or other material which may be secured in place by inserting a shank 15 thereon in a recess located in a plunger operated by the handle 12.

Opposite the die 14 is a base 16, the upper edge of which is roughened as at 17 to provide a gripping surface for the lower die.

In manufacturing seals it is customary to first construct the die 14 with the letters in

relief thereon after which the other die member is placed beneath the die 14 and the companion letters are formed therein.

Heretofore the lower die has been constructed from a metal alloy which has not proved altogether satisfactory in use. After much experimenting, I find that material known to the trade as bakelite may be used, and that the use of this material produces a highly superior article and at reduced cost.

The properties of bakelite are such that after being heated and allowed to set it is not affected by reheating. Moreover it is not liable to become dented easily, thus prolonging the life of the seal and moreover the seals are more easily manufactured from bakelite.

In using bakelite or other similar composition I preferably provide a heating tool which is shown at 20. This heating tool comprises an intermediate body portion 21 which is provided with cylindrical heating elements 22 arranged at each side thereof. The heating elements 22 are connected through leads 23 and 24 through a thermostatically controlled circuit closing device 26 with leads 27 and 28 which may be in communication with a source of electricity.

The circuit closing device 26 which is shown as arranged on the lead 11 comprises circuit closing members 30 and 31. The member 31 is mounted on a heat responsive element 32 which is preferably curved as shown and is composed of the layers of metal having different coefficients of expansion so that when the member is heated or cooled its length is altered.

The element 32 is secured at one end in the base portion 21 of the tool so that this element will be affected in accordance with the temperature of this base member.

In using the heating element it is placed with the base 21 beneath the upper die 14. The handle 12 is then operated and the heating element is held firmly between the base 16 and the upper die 14. When these portions have been raised to the proper temperature the heating element is removed and a contractile band 30 which is shown in Fig. 4 is placed upon the base 16.

The band shown in Fig. 4 comprises a strip of thin flexible metal having the ends thereof secured to brackets 35 and 36. The bracket 35 is provided with a pair of links

37 which pivotally connect a locking member 38 which has a cam 39 on the end thereof. The construction is such that when the arm 38 is turned to the position shown in 5 Fig. 4 the band will be held in retracted position.

After the band has been placed on the base 16 and before it is contracted a disc of bakelite is placed within the band. The 10 bakelite disc is preferably of the same size as the die 14. The band is then tightened to engage the periphery of the die 14 and bakelite disc. The handle 12 is next operated to bring the die 14 upon the bakelite 15 disc. This causes the bakelite to soften due to the heated condition of the parts 14 and 16 so that the characters in the portions 14 are impressed in the bakelite. After the parts have cooled the contractile 20 band is removed and the seal is ready for use.

In Fig. 5 I have shown a modified heating element wherein the base 50 is slotted as at 51 so that it may slide over the shank 25 52 (see Fig. 6) of the seal 53. Heating elements 54 are arranged at each side of the base 50. A thermostat 55 similar to the thermostat 32 may control the circuit to the elements 54.

30 The seal here shown is provided with a base 56 which has apertures 57 therein adapted to be closed by plugs 58. The upper portion of the base is serrated as at 59.

In using the device shown in Fig. 5 the 35 heating element and the bakelite disc are both inserted with a band 30 about the bakelite disc. The upper die 52' which is preferably made of material such as brass, is then brought down upon the disc. Heat 40 from the base 50 will pass to the die 52' and will heat the bakelite as previously described.

The bakelite disc which is used is shown 45 in Fig. 7 at 60. I preferably use a circular disc having planar upper and lower surfaces as shown. The roughened surfaces 17 and 59 serve to hold the lower die in place. A thermostat may be used to control the heating elements 54 if desired.

50 With the use of my invention seals may be made without raising the temperature of the body of the die to a point where the finish of the die would be effected. Furthermore, when the thermostatic control is 55 used the heat applied may be completely

controlled to secure efficient operation.

Having thus described my invention, I claim:

1. In combination with a seal having a base, means to hold a disc upon said base, said means comprising a flexible band adapted to engage said disc and means to alter the size of said band and to hold the band in adjusted position.

2. In combination with a seal having a base thereon, a disc on said base, means to render said disc plastic, a band for engaging the periphery of said disc, said band having a pair of brackets thereon and means to urge said brackets together to tighten said band, said last mentioned means comprising a locking lever.

3. In combination with a seal having a base, means to hold a disc upon said base, said means comprising a contractile band adapted to engage said disc, said seal having a plunger thereon including a die, said band being normally larger than said die and means to reduce the diameter of the contractile band.

4. In combination with a seal including a body portion having a base thereon and a plunger having a die thereon, means to actuate said plunger, said base portion having gripping portions thereon and having a disc 65 thereon, said die being made of plastic material such as a condensation product of phenol and means movable with said plunger to heat the die and said base.

5. A seal comprising a body portion having a base thereon, a plunger having a die thereon, means to actuate said plunger, said base having gripping portions thereon and having a die thereon, said last mentioned die being made of material comprising a condensation product of phenol, said material being embedded in the gripping portions.

6. In combination with a seal including a body portion having a base thereon, a disc upon said base, said disc being constructed of material plastic under heat, a die movable toward said base and having characters thereon, means to move said die and means movable with said die to heat said die, and a band surrounding said die and said disc.

In testimony whereof, I hereunto affix my signature.

SAMUEL A. HAMNETT.
